UNITED STATES PATENT OFFICE

2,616,367

COATING DEVICE

Abraham Sprung, Brooklyn, N. Y.

Application April 4, 1952, Serial No. 280,553

10. Claims. (Cl. 101—329)

1

This invention relates to a coating device of the roller type which is further illustrated by my co-pending application Serial No. 241,904, filed April 9, 1951. The purpose of the structure is for coating or printing continuous surfaces or applying designs to such surfaces by the use of paint or other coloring material which may be applied as desired to walls, ceilings, cloth or other material.

The main purpose of the invention is to provide a rigid structure of the type set forth in which the coating roll is carried by a removable bracket, the bracket being so constructed and arranged as to be interchangeable for use with applicator rolls having handle structures of modified designs.

A further object of the invention is to provide a bracket for supporting a coating roll in which the coating roll is capable of adjustment along its own axis, adjustable angularly with reference to its longitudinal axis and further adjustable for the purpose of varying the pressure between the applicator roll and the coating roll.

Other features of the invention will more clearly hereinafter appear by reference to the accompanying drawings forming a part of the application in which like characters of reference designate corresponding parts throughout the several views, in which:

Fig. 1 is a side elevation with parts broken away in section showing the invention assembled with one type of applicator roll;

Fig. 2 is an end elevation of the main bracket element;

Fig. 3 is a longitudinal section through the bracket of Fig. 2 showing a portion of the hub handle in position;

Fig. 4 is a view showing the bracket parts disassembled;

Fig. 5 shows the coating roll bracket applied for use with a modified form of applicator roll handle structure;

Fig. 6 is an end elevation of the structure of Fig. 5;

Fig. 7 is a longitudinal section through the bracket structure and illustrates a portion of the handle in position in the bracket opening; and

Fig. 8 is a perspective view of a wrench used in the structure.

Referring now to Fig. 1, the applicator roll is shown at A. This applicator roll A may be of the fountain or contact type and normally provides the coating material which is picked up through contact by the coating roll B and applied to a surface. The applicator roll A is provided with

2

means for manually utilizing the same, this means including a handle 1 having a shank structure connected thereto by any suitable means as shown at 2, the shank structure being bent at right angles immediately adjacent its connection with the handle 1 as shown at 3, and projecting laterally as at 4 to a point beyond the end of the applicator roll A where it is again bent at substantially right angle for a distance to provide a portion 5 of such a length as to provide clearance between the applicator roll A and the lateral shank portion 4. The end of the shank portion 5 terminates in an elongated inwardly projecting hub 6, the axis of which is substantially parallel to the horizontal shank portion 4 of the handle structure, this hub 6 being adapted to be contained within a cylindrical opening formed in the main element of the bracket attachment as will be more fully hereinafter described.

The structure of the handle in that form of the invention shown in Fig. 1 includes an inwardly projecting rib 7 which is shown to extend throughout the length of the shank handle and to terminate at the hub 6 in an arcuate inwardly projecting portion 8, as shown more clearly in Fig. 3. The rib 7 adds substantially to the rigidity of the shank structure but could extend only throughout the portion 5 of the shank and at the hub 6, in which area it cooperates with the coating roll attaching bracket. It is intended that the length of the hub 6 will be such as to abut the end wall 9 of the applicator roll and position this roll on its supporting pin 10, properly spaced from the offset portion of the shank and of the bracket structure, to provide ample clearance for the operation of the device. The supporting pin 10 may be permanently secured to the applicator roll and this roll will rotate with its supporting pin 10 within a bearing sleeve 11 arranged within the hub 6, or if desired the roll could be mounted for free rotation on the pin structure. In the present illustration the roll rotates with the pin 10 within the hub 6, as shown, and the end of the pin is clamped against axial displacement by the nut 12 which can be fixed against rotation by a superimposed lock nut structure 14.

The foregoing structure provides an applicator roll having a handle medially positioned with respect to its length, with the shank of the handle offset and providing a hub structure in which the supporting pin for the applicator roll is mounted against longitudinal displacement. The main inventive concept is the use of the bracket element 15 shown in perspective view in Fig. 4.

This bracket structure includes a tubular body 17 having at its outer end an upwardly projecting plate extension 18 terminating in a tubular extremity 19, the opening in the tubular extremity 19 having its axis normally parallel to the axis of the supporting pin 10 of the applicator roll. The length of the plate extension 18 is such as to position the tubular extremity 19 at such a distance from the tubular body 17 that the coating roll B carried thereby will be properly spaced from the applicator roll A as will be obvious from an inspection of the drawing.

A depending projection 20 extends from the outer lower portion of the body 17 and is provided with an internal, outwardly facing slot 15 having an arcuate portion 21 and a substantially straight portion 22 for the purpose of receiving and confining the arcuate or upper portion 8 of the rib 7 of the upper portion of shank 5, and the portion of the rib immediately joining the arcuate portion thereof. The purpose of this recess 21—22 in the body 17 of the bracket member is to suitably embrace and snugly receive the shank rib and thereby retain the bracket against rotational movement about its axis, which latter axis is formed by the hub 6 at the upper end of the shank 5. The hub 6 extends into and through the tubular body 17 of the bracket and these parts are further secured by means of the screw or bolt 23 which may be seated by a wrench such as shown in Fig. 8. By the structure set forth the main bracket structure is secured about the hub 6 against rotational movement on its own axis as well as against longitudinal movement on the hub, and the coating roll B which is supported by the extremity of the bracket structure and by the hub portion 19 at the end thereof will be firmly fixed in position and readily removed when desired.

The coating roll B has its outer surface provided with suitable configurations 25 and is of tubular form with its interior formed with spiral ribs 26 for convenient positioning on the cylindrical core block 27 which is contained in the coating roll structure. A bolt 28 extends through the core 27 with the bolt head 29 received in the socketed end of the core and with its free end projecting through the opening in the hub extremity 19 of the main bracket. The opening 30 at the end of the bracket is elongated vertically to permit vertical adjustment of the coating roll B and its supporting structure, and this coating roll B is secured in position by a clamp provided by the spaced nuts 31 and 32. The nuts 31 and 32 are threaded on the threads of the free end of the bolt 28 and are adjustable therewith to position the coating roll B axially and with respect to the applicator roll A. The outer nut 32 clamps the hub extremity 19 against the inner nut 31 and a wedge washer 33 is provided between the inner nut 31 and the adjacent face of the hub extremity 19 to vary the pitch of the coating roll B and its carrying pin or bolt 28 where this is necessary due to deformation of the applicator roll A through use, accident or otherwise, and in order that the rolls may at all times have their axes parallel so that the transfer of the coating material will be constant throughout.

In Figs. 5, 6 and 7 a modified form of shank is illustrated. In this disclosure the same bracket is utilized with the same type of applicator roll A and coating roll B. For this reason the same reference characters are applied to the bracket in the modification to indicate the various parts.

In the structure of the modification the shank is formed of a one piece rod which has the portion 40 connected to a handle such as handle 1 of Fig. 1. The shank of the rod 40 is bent at right angle as at 41 to provide the offset vertically extending portion 42 by the second right angle bend 43 formed laterally of the applicator roll A. The end of the shank 42 is bent laterally at 44 and a distance approximating the length of the tubular portion 17 of the bracket as shown at 44, the portion of the rod forming the lateral bend as at 45 being arcuate and the curve approximating the arc of the recess 21 of the bracket. The rod portion 44 is bent upon itself as at 45 and extends inwardly as at 46 to provide a supporting pin for supporting the applicator roll. The means of fastening the applicator roll on the pin extension 46 forms no part of the invention but normally this pin will be provided with screw threads 47 and nut 48 in the usual manner as indicated generally in Fig. 7 to permit the clamping of the applicator roll A on its length in suitably adjusted position.

In use of the form of the invention shown in Figs. 5 through 7, as clearly shown, the main bracket element assumes a position the reverse from its position in the disclosure of Fig. 1 in that the flat elongated wall portion faces inwardly to position the arcuate slot 21 in a position to receive the arcuate portion 43 of the shank or handle. It will be obvious to one skilled in the art that the rod structure from which the modified form is to be made must be of a diameter that when it is bent upon itself for reception within the attaching bracket, it will comprehend a thickness no greater than the opening in the cylindrical portion 17 of the bracket and when so positioned it will be secured in place by set screw 49 or other suitable fastening as in the previous disclosure. Obviously, rotational movement of the bracket in the modified form is prevented by the reception of the portions of the shank 42 and 43 in corresponding portions of the recess 21 and 22 of the bracket. This form of the invention is obviously one which can be made very easily and cheaply, but is convertible for use with an applicator roll by the utilization of the structure of the present invention.

In the modification shown in Figs. 5 through 7, the flattened area 43 which is received in the arcuate recess 21 in the bracket should be of a cross sectional diameter approximately identical with the rib portions 7 and 8, as these portions are designed to be associated with an interchangeable bracket. The exact measurements of the parts may be modified in different models of the same general form, as long as the associated elements comprehend interchangeability.

What I claim is:

1. In combination, a coating device including a roll, a handle, and a connecting shank structure, said connecting shank structure including an offset portion lying laterally of the roll, and a mounting pin for the roll connected to the end portion of the offset portion, said shank at its junction with the pin including an arcuate laterally projecting portion, a bracket having a cylindrical body portion for receiving an end portion of the pin, and an arcuate recess for receiving said arcuate projecting portion, means for clamping the bracket in position embracing said pin and arcuate portion, and a mounting at the end of the bracket for a coating roll, said mounting being supported at the end of the bracket for angular and transverse adjustment.

5

2. The structure of claim 1 characterized in that the bracket includes a cylindrical body portion and two projecting portions extending laterally from one end of said cylindrical body portion, one of the projecting portions carrying an inwardly projecting hub and the other projecting portion including an arcuate slot.

3. The structure of claim 1 characterized in that the mounting at the end of the bracket for the coating roll includes an inwardly projecting hub having its axis lying parallel to the axis of the cylindrical body.

4. The structure of claim 1 characterized in that the mounting for the coating roll includes means for providing transverse and lateral adjustment of the roll, and additional means for providing for angular adjustment of the roll with respect to the cylindrical body portion.

5. The structure of claim 1 characterized in that the cylindrical body portion of the bracket is provided with a web-like extension which includes an arcuate slot terminating in a relatively straight slot portion which receives similarly shaped web-portions projecting from the shank.

6. The structure of claim 1 characterized in that the shank is formed from a single piece of metal rod which is bent to provide an offset portion terminating in a roll supporting shaft, the junction of the shaft with its main shank portion including an arcuate section to be received in the arcuate recess of the bracket.

7. The structure of claim 1 characterized in that additional means are provided for securing the bracket against rotational and axial displacement with respect to the cooperating shank portion.

8. In combination, a coating device including an applicator roll, a handle, a connecting shank

6

structure, said shank structure including an offset portion lying laterally of said roll, and a mounting pin for the roll connected to the end portion of the offset portion, said shank at its junction with the pin including a laterally projecting wall, a bracket having a cylindrical body portion for receiving an end portion of the pin, and a recess for receiving said laterally projecting wall to embrace the same to prevent rotational movement of said bracket, means for clamping the bracket into position embracing said wall, and a mounting at the end of the bracket for a coating roll, said mounting being supported at the end of said roll for adjustment with respect to the applicator roll.

9. The structure of claim 8 characterized in that the end of the offset portion includes an inwardly projecting hub and the projecting wall portion connects the hub and the offset portion of the shank.

10. In combination, a coating device including an applicator roll, a handle, a connecting shank structure, said shank structure including an offset portion lying laterally of said roll, said offset portion terminating in an elongated hub structure, a web connecting the hub structure and the offset portion of the shank, and a bracket for supporting a coating roll, said bracket including a cylindrical portion for enclosing said hub, a projecting portion having a recess for receiving said web, and a second projecting portion terminating in a hub structure for adjustably receiving the supporting pin of said coating roll.
